BALANCED RELAY

Robert S. Curry, Jr., Baldwin, John H. Horman, Tuckahoe, and August C. Kircher and Herbert Winsker, Jackson Heights, N. Y., assignors, by mesne assignments, to Allied Control Company, Inc., New York, N. Y., a corporation of New York

Application March 2, 1943, Serial No. 477,750

5 Claims. (Cl. 200—98)

1

This invention is directed to relays, more particularly, to relays of the balanced type.

It is among the objects of the present invention to provide a balanced relay wherein slight changes of current passing through a pair of coils is adapted to make or break circuits and to maintain such circuits firmly against vibration.

It is also among the objects of the present invention to provide a structure wherein the movements of the armature of the relay will give a wiping action on the contacts, closing a circuit firmly so as to avoid chattering and resist external vibration without losing the contact.

It is further among the objects of the present invention to provide a structure which is responsive to extremely small changes of currents and has a delicate balance, but which is protected against outside forces so that the relay will withstand severe service.

It is still further among the objects of the present invention to provide a relay structure which is adapted for large quantity production, which may be assembled in several units, which lends itself to ready replacement of parts, wherein the various terminals are readily accessible, and which may be secured to various types of supports.

The novel construction of the present invention is illustrated in the drawings constituting a part hereof and in which like reference characters indicate like parts, wherein:

Fig. 1 is a side elevational view of the new relay with the lower supporting member bent out of line to better illustrate the structure;

Fig. 2 is an end elevational view thereof;

Fig. 3 is a top plan view thereof;

Fig. 4 is a bottom plan view thereof;

Fig. 5 is a vertical cross-sectional view taken along the line 5—5 of Fig. 1;

Fig. 6 is an enlarged fragmentary cross-sectional view of the contact making members and associated parts;

Fig. 7 is a view taken along the line 7—7 of Fig. 6, some parts being shown in cross-section for clearness; and

Fig. 8 is a fragmentary side elevation showing a modification.

There is provided a metal base 1 having mounted thereon a pair of coils 2 and 3 with a metal bar 4 of magnetic material placed between said coils. Each of the coils is provided with a central core 5, and screws 6 passing through base 1 hold the coils in position with their axes parallel. The base has a pair of ears 7 and 8 bent upwardly and embracing the sides of bar 4, and screws 9 firmly secure the same to bar 4.

A supporting plate 10 below base 1 is spaced therefrom by spacer 11 and is secured to said base and bar 4 by screws 12. Plate 10 has a pair of openings 13 sufficiently large to fit loosely over

the heads of screws 6. Nuts 14 mounted on the ends of plate 10 provide means for securing the same to a suitable base. Because base 1 and plate 10 are not connected except at a central point, if the surface on which the relay is to be mounted is irregular, the plate 10 may be bent in any desired manner so as to be capable of firm attachment to the support. This is indicated at the lower left side of Fig. 1 wherein the plate is shown bent to accommodate an irregular surface.

Above the coils is provided a metal contact support having the opposed sides 16 thereof bent downwardly to form ears embracing bar 4, and thin metal plates 17 are placed on the outside thereof. It is secured to bar 4 by screws 18. By this construction an uninterrupted magnetic path is provided so that flux may readily flow through each core 5, base 1, bar 4 and the armature of the relay. The armature 19 overlies both of the coils and has a pair of ears 20 formed along the central portion of the sides thereof, said ears accommodating a pin 21 which is held in ears 16.

An insulating plate 22 is carried by the contact support 15. Secured to the upper side of the plate 22 is an insulating block consisting of a plurality of insulating plates or laminae 24, 25, 26, 27, 28 and 29 of different lengths, widths and thicknesses forming longitudinal recesses. The plates 24, 25 and 26 are approximately the same length as the plate 22 while the plate 25 is of less width than the plates 24 and 26 to form a longitudinal recess in which is arranged a spring metal contact piece 30 having its ends projecting beyond the ends of the plates 24, 25 and 26 and being provided at its ends with terminal buttons 31 overlying the ends of the armature 19. Also, in the recess is provided a terminal member 32 underlying the contact piece 30 and projecting beyond the face of the insulating block. The plate 27 is of the same width as, but slightly longer than the plates 24 and 26 while the plate 28 is of the same length as the plate 27 but of less width to form a longitudinal recess in which is arranged a pair of longitudinally spaced contact pieces 33 having their ends projecting beyond the ends of the plate 27 and each contact piece having a contact button 34 in co-operative relation with a terminal button 31. Also, in the recess is provided a terminal member 35 underlying each contact piece 33 and projecting beyond the face of the insulating block. The plate 29 is of the same width as the plate 27 and is of sufficient length to overlie the ends of the contact pieces 33 while the relative dimensions and positions are such that a space intervenes between the plate 29 and the buttons 34. On the plate 29 is placed a metal protector 36 of stiff material and the several metallic and insulating members are held together as a unit by screws 37.

The contact piece 30 is biased so that its ter-

terminal buttons 31 engage the ends of the armature 19 and by spring pressure hold the same in adjusted position. Also, the contact pieces 33 are biased toward the armature.

Each of the ends of armature 19 is provided with an upwardly extending member 38 on the outer face of which is held threaded insulating member 39. Said member is provided with a pair of semi-cylindrical recesses 40 in which the threads are located. A covering member 41 also has a pair of recesses 42 provided with complementary portions of the threads which are formed in recesses 40. An adjusting screw 43 is held in the opening formed by recesses 40 and 42 and carries in the head thereof a contactor 44 of insulating material. A set screw 45 holds the assembly in fixed position, as shown in Fig. 7. While in Fig. 7 only one screw 45 is illustrated and in the drawings only one set of contacts is shown, because of the construction it is possible to introduce an additional contact piece like 30 parallel thereto, and insert an additional number of screws 43 and all associated parts so as to control four circuits instead of two, as shown and described.

The plate 22 has two pairs of terminal members 46 and 47. Connections 48 are made from the coil 2 to the terminal members 46 and similar connections 49 are made from the coil 3 to the terminal members 47. The free ends 50 of said terminal members provide means for attaching the coils to a suitable control circuit. As shown in Fig. 8, a transparent shield 51 of suitable insulating material is supported in position to enclose the contacts 31 and 34. The shield 51 is held in place by a screw 52 passing therethrough into the metal plate 36.

In the operation of the device current from control circuits is caused to flow through coils 2 and 3. When the relay is in inoperative position, the magnetic fields set up in the coils are equal and the magnetic force holds the armature in neutral adjusted position, as shown in Fig. 1. Because of the balancing action of spring contact piece 30 and the force of the magnetic field the relay is held in balanced position so firmly that even severe vibration on the outside or application of blows, will not close the circuits. If, however, the magnetic fields set up by coils 2 and 3 are unbalanced even by a small amount of current change, a positive force is exerted, pulling armature 19 on one side or the other, thereby closing the circuit on the opposite side. Referring more particularly to Fig. 6, when the end of armature 19 is caused to move upwardly, button 31 being in contact with contactor 44, contact is made with button 34. Movement continues and because button 34 moves further, a rubbing or wiping action takes place between buttons 31 and 34, thus insuring good electrical contact. When button 34 is in firm contact with plate 29, a firm electrical contact is made. In this position even severe vibration is ineffective to loosen a contact or open the circuit.

Even though the operating elements of the balanced relay are in themselves of delicate construction and light in weight, the relay as a whole is very sturdy. Because of the double base and the heavy metal bar on the top of the relay, and because the terminals are within the general area of the relay and the delicate contacts are centrally located within the relay, the latter may be subjected to extremely severe conditions without damage to the delicate elements. This is of extreme importance particularly where the re-

lay is to be used in vehicles of various types which are subject to severe shocks in service.

The relay as a whole is made up of several units. The coils and base are constructed as a unit which may be readily attached or detached from the bar 4. Similarly, the various insulating plates and top protector, together with the contact pieces, are assembled as a unit and this unit may be secured to insulating plate 22. The armature and its associated parts are mounted in contact support 15 and the latter may be secured to the assembly by the use of a few screws. From this it will be seen that in the manufacture of the relay it is possible to make several sub-assemblies by specialized labor whereby economy in production is obtained. The sub-assemblies may then be easily united to complete the relay.

Although we have described our invention setting forth a single embodiment thereof, said embodiment was described for purposes of illustration only and it is not to be considered as limiting the invention. Those skilled in the art will readily appreciate that various details of construction may be changed at will while adhering to the principles set forth herein. The forms of the several members may be changed, as is well known, and the materials used may be other than those herein described. Therefore, the invention is to be broadly construed and not to be limited except by the character of the claims appended hereto.

What we claim is:

1. A balanced relay comprising a pair of magnetic coils having their axes parallel and mounted on a common base of magnetic material, a bar of magnetic material between said coils and secured to said base, a balanced armature pivoted above and overlying said coils, an insulating member above said armature, a contact piece on one face thereof extending beyond the ends thereof, and a pair of contact pieces on the other face cooperating with said first contact piece, said first contact piece being of spring metal and having its ends biased into engagement with the ends of said armature to balance the latter against vibration.

2. A balanced relay comprising a pair of magnetic coils having their axes parallel and mounted on a common base of magnetic material, a bar of magnetic material between said coils and secured to said base, a balanced armature pivoted above and overlying said coils, an insulating member above said armature, a contact piece on one face thereof extending beyond the ends thereof, a pair of contact pieces on the other face cooperating with said first contact piece, said first contact piece being of spring metal and having its ends biased into engagement with the ends of said armature to balance the latter against vibration and each of the two remaining contact pieces being of spring metal having their ends biased toward said armature.

3. A balanced relay comprising a pair of magnetic coils having their axes parallel and mounted on a common base of magnetic material, a bar of magnetic material between said coils and secured to said base, a balanced armature pivoted above and overlying said coils, an insulating member above said armature, a contact piece on one face thereof extending beyond the ends thereof, a pair of contact pieces on the other face cooperating with said first contact piece, insulating elements covering said pieces, said first contact piece being of spring metal having its ends biased into engagement with the ends of said

armature to balance the latter against vibration and a contact supporting member secured to said bar, said insulating member and elements and said contact pieces being secured to said bar.

4. A balanced relay comprising a pair of magnetic coils having their axes parallel and mounted on a common base of magnetic material, a pivoted balanced armature above and overlying said coils, an insulating member above said armature, a contact piece on one face thereof extending beyond the ends thereof, and a pair of contact pieces on the other face co-operating with said first contact piece, said first contact piece being of spring metal and having its ends biased into engagement with the ends of said armature to balance the latter against vibration.

5. A relay according to claim 4 characterized by each of the two remaining contact pieces being of spring metal and having their ends biased toward said armature.
